[57] CLAIM

The ornamental design for a syringe for administration of contrast media, as shown and described.

DESCRIPTION

FIG. 1 is a perspective view of a syringe for administration of contrast media, showing my new design;

FIG. 2 is a front elevational view thereof, the rear elevational view being identical;

FIG. 3 is a side elevational view thereof rotated 90 degrees relative to FIG. 2, the opposite side elevational view being identical;

FIG. 4 is a top plan view thereof; and

FIG. 5 is a bottom plan view thereof.

FIG. 1

FIG. 2

FIG. 3

FIG. 4

FIG. 5
